UNITED STATES PATENT OFFICE

127,810

DESIGN FOR A STOOL

Lawrence M. Michelson, Clayton, Mo.

Application April 22, 1941, Serial No. 100,565

Term of patent 7 years

To all whom it may concern:

Be it known that I, Lawrence M. Michelson, a citizen of the United States, residing at Clayton, in the county of St. Louis and State of Missouri, have invented a new, original, and ornamental Design for a Stool, of which the following is a specification, reference being had to the accompanying drawing, forming part thereof,

The drawing is a view in perspective of a stool embodying my new design.

I claim:

The ornamental design for a stool, substantially as shown.

LAWRENCE M. MICHELSON.
